Fig. 5

—+— 3
Fig. 3

FIG. 1 is a perspective view of a utility tray, showing my new design;

FIG. 2 is a top plan view;

FIG. 3 is a front elevational view taken substantially along line 3—3 in FIG. 2, the rear having substantially the same appearance;

FIG. 4 is a cross-sectional view, partly in end elevation, taken substantially along line 4—4 in FIG. 3; and

FIG. 5 is an end elevational view thereof, the opposite end having substantially the same appearance.

I claim:

The ornamental design for a utility tray, substantially as shown and described.
